GAS LIFT MEANS

Application filed June 18, 1928. Serial No. 286,124.

This invention relates to gas lifts and is more particularly related to a gas lift adapted for use in elevating oil or like liquids from wells, and is particularly addressed to a type 5 of gas lift apparatus which may be submerged in the oil within a well to any desired or required degree, and is not dependent for its operation upon the degree of submersion of the apparatus in the oil within 0 the well but is capable of a constant and predetermined operation irrespective of the degree of submersion.

Heretofore many types of gas lifts have been employed for the purpose of forcing 5 liquids such, for example, as oil, water and the like, from wells drilled in the ground. The gas lifts as heretofore used, for the most part, have been of such a construction and mode of operation that they have required 10 that they be submerged a definite head into the column of the liquid within the well in order that they will function correctly and economically. To maintain the correct degree of submergence of an apparatus within 15 an oil well so that the operation of the gas lift apparatus will be constant is extremely difficult and practically impossible, due to the fact that the head of the liquid within the well will vary due to many causes such, for 20 example, as the variation of rock pressure which raises the column of oil in the well.

It is, therefore, an object of this invention to provide a gas lift apparatus which is constructed to permit the same to be submerged 25 in the column of liquid in the well to a point near the bottom thereof or to any desired degree so as to eliminate the necessity of setting the apparatus to a definite predetermined degree of submergence and which apparatus includes a means for admitting into the gas lift chamber of the apparatus a predetermined charge of oil or like liquid which may be forced from the well as a slug.

Another object of this invention is to provide a gas lift including a single valve mechanism which is of the equalized type and is operated automatically by fluid pressure in order to intermittently admit the liquid from 50 the well to the gas chamber and intermittent-

ly force the liquid as admitted into the gas chamber from the gas chamber as a slug.

Other objects and advantages of this invention it is believed will be apparent from the following detailed description of a preferred embodiment thereof as illustrated in the accompanying drawings:

In the drawings:

Figure 1 is a diagrammatic sectional elevation of a well illustrating a gas lift mechanism as submerged in the column of oil within the well.

Figure 2 is a sectional elevation of the gas lift mechanism embodied in this invention.

Figure 3 is a sectional end elevation taken 65 substantially on the line 3-3 of Figure 2.

Figure 4 is a sectional end elevation taken substantially on the line 4-4 of Figure 2.

Figure 5 is a sectional end elevation taken 70 substantially on the line 5-5 of Figure 2.

Figure 6 is a diagrammatic sectional elevation of a well illustrating a modified form of gas lift apparatus as embodied in this invention.

Figure 7 is a sectional side elevation of the 75 modified form of gas lift apparatus embodying this invention.

Figure 8 is a sectional end elevation taken substantially on the line 8-8 of Figure 7.

In the preferred embodiment of this invention as illustrated in the accompanying drawings, 1 indicates a well casing to the lower end of which is secured a well screen 2 which may be of any suitable or desirable construction, as is well understood in the art, 80 for admitting the oil or other liquid from the formation into the casing 1. Concentrically mounted within the casing 1 is a tubing 3, and concentrically disposed within the tubing 3 is a string of macaroni tubing 4. Suspended 85 from the lower end of the tubing 3 is the gas lift apparatus embodied in this invention.

Secured to the lower end of the tubing 3 is a sleeve 5 which is connected at its upper end to the tubing 3 and at its lower end to a barrel 6. The barrel 6 provides a gas lift chamber 7 into which the liquid to be elevated from the well is admitted, and the barrel 6 is provided with an inlet valve 8 95 at its lower end and at its upper end is in 100

open communication with the tubing 3. Secured within the sleeve 5 is a block 9 which provides a seat 10 for the gas inlet valve 11. The block 9 is provided with a plurality of ports 12 through which the liquid and gas from the chamber 7 is forced.

The macaroni tubing 4 is releasably connected with a sleeve 13 which is connected with a housing member 14 secured to the block 9. The housing 14 provides a housing for the gas inlet valve 11.

The macaroni tubing 4 is secured to the sleeve 13 by means of a pin 15 secured to the lower section of the macaroni tubing 4 and passes into a lock slot 16 formed at the upper end of the sleeve 13.

Means are provided for packing the macaroni tubing 4 within the sleeve 13, which means may be of any suitable or desirable form, as illustrated by the packing cup construction 17 which surrounds the lower end of the lower section of macaroni tubing 4 and packs outwardly against the sleeve 13.

Mounted within the lower section of macaroni tubing 4 is a check valve 18 which is yieldably held in position by means of a spring 19 to prevent the well liquid from passing into the macaroni tubing 4 when the macaroni tubing is lowered into position within the sleeve 13.

In order to admit a predetermined slug of liquid or oil to be raised from the well and to admit a predetermined quantity of gas into the gas chamber 7 to force the liquid as admitted to the chamber 7 from the well, automatically operating valve means are provided which are preferably of the following construction:

The inlet valve 11 is provided with a guide stem 20 which fits within a guide sleeve 21 formed in the housing 14. Formed through the stem 20 and the valve-head 11 is an equalizing port 22 which equalizes the pressure in the opposite faces of the valve 11 so that the valve 11 will actuate by gravity when so permitted. The liquid inlet valve 8 is also provided with a guide stem 23 which fits within a guide 24 formed as an extension of the cage 25 within which the valve head 8 is mounted. The cage 25 is secured at its upper end to a seat block 26 which provides a valve seat 27 for the valve head 8. The block 26 is screw-threaded to the coupling member 271 by means of which the chamber 7 is coupled to the lower extension 28 of the tubing 3. An equalizing port 29 is formed through the valve head 8 and stem 23 so as to equalize the pressure upon the opposite ends of the valve structure. Mounted within the chamber 7 is means for automatically actuating the valves 8 and 11, which means preferably includes a bellows 30 which is mounted concentrically around a stem 31. The stem 31 is secured to a connecting rod 32 which connects with the valve head 8. The

stem 31 is formed with an extension 33 of the equalizing port 29. Secured to the upper end of the stem 31 is a stop plate 34 which is adapted to engage the end plug 35 of the housing 36 which encloses a balancing spring 37 which exerts pressure downwardly on the stem 31 to force the stem 31 downwardly, and hence force the valve head 8 away from its seat 27 to overcome the pressure created by the column of fluid desired in the chamber 7 and tubing 3.

The spring 37 engages at its opposite end a plug 38 which is screw-threaded within the housing 36. The housing 36 is screw-threaded to the end of the sleeve 5. The spring 37 is mounted to permit its operating pressure to be varied by screwing in or out the cap 38 so that the column of liquid which is to be forced from the well as a slug may be varied. The setting of the spring 37 determines the height of the column to be forced from the well as a slug by providing means for equalizing the pressure exerted on the bellows 30 by such a column of fluid.

A perforated plate 39 is secured to the stem 32 by means of a lock nut 40 and the plate 39 is perforated as illustrated at 41 to permit the well liquid to pass into the chamber 7 and tubing 3. Secured to the plate 39 are guide rods 42 which pass upwardly from the plate 39 through guide bores 43 formed in the transverse extension of the housing 36 and are connected with a second perforated plate 44. Secured to the upper perforated plate 44 is a plunger 45 which extends upwardly into position to engage the inlet valve 11 to raise the valve 11 from its seat and permit gas to flow downwardly into the gas chamber 7 and tubing 3 to lift the oil or liquid from the well when the pressure within the chamber 7 has been built up sufficiently by the admission of the well liquid into the chamber 7 and tubing 3 to cause the bellows 30 to operate to raise the valve head 8 against the seat 27. The housing 36 is filled partially with a liquid and the remainder of the volume of the housing 36 is filled with air so as to partially equalize the pressure on the bellows 30 and to provide a fluid stop to prevent the bellows 30 from collapsing from external pressure created in the barrel 6 when the gas under pressure is admitted to raise the column of liquid as a slug from the well, or created by other variable circumstances beyond definite control.

In the modified form of this invention illustrated in Figures 6, 7 and 8, the structure is entirely similar to that illustrated in Figures 1, 2, 3, 4 and 5 so that the same numerals have been used with the addition of an exponent "a" to designate the parts of this modified structure, the essential difference between the two structures being that in the second form the casing 1^a is used to provide the gas conducting pipe, and the tubing 3^a 130

is used to conduct the fluid and gas from the well. This construction eliminates the use of the macaroni tubing 4 required for the construction illustrated in Figures 1 to 5 inclusive.

In order to conduct the gas into the lift mechanism when using this type of construction, it is necessary to modify the construction of the gas inlet valve to provide a ported block 50^a which is screw-threaded in the sleeve 5^a which connects the tubing 3^a with the barrel 6^a. The ported block 50^a is provided with transversely extending ports 51^a for the admission of the gas from the casing 1^a into the chamber provided by the barrel 6^a. The block 50^a is also provided with vertically extending ports 52^a to permit the gas and fluid to pass outwardly through the tubing 3^a. The valve 11^a having a guide stem 20^a is mounted in the block 50^a to engage the seat 10^a, and a guide 53^a is secured to the block 50^a to guide the stem 20^a.

In this latter type of construction in order to prevent the imposing upon the column of liquid in the well and hence upon the formation of the gas pressure, it is necessary to provide a packer 54^a at the lower end of the lift assembly which packs the extension of the tubing 3^a against the casing 1^a.

In the case of each construction the gas inlet conduit, whether it be the macaroni tubing 4 or the casing 1^a, is connected with a suitable source of gas under pressure and may be connected with a multiple well operating mechanism such, for example, as illustrated in my co-pending application for gas lift method and means Serial No. 178,962, filed March 28, 1927. The fluid lifted from the well may be conducted to any suitable source such, for example, as a gas trap in order to separate the gas from the well liquid.

The operation of the gas lift embodying this invention is that gas under pressure is admitted to the lift chamber under a predetermined height of liquid irrespective of the degree of submergence of the apparatus in the column of liquid in the well and is so admitted only when the column of liquid has been built up in the delivery pipe to a sufficient head to compress the bellows 30 or 30^a and hence raise the valve head 8 or 8^a against its seat and close off the column of liquid from the well.

The gas is then admitted to below the column of liquid from the well as a slug and when the slug has been lifted from the well, the pressure within the chamber 7 becomes reduced and the spring 37 and bellows 30 are operative to again move the valve 8 away from the seat 27 and hence permit the valve 11 to seat on its seat 10 and close off the gas from the lift chamber and permit oil to flow freely from the well into the chamber 7 and tubing 3 to the predetermined height, which is determined by the pressure of the spring

37 or 37^a when considered with the pressure created by the compressed air trapped within the housing 36.

Having fully described my invention, it is to be understood that I do not wish to be limited to the details of construction herein set forth as my invention is susceptible to various modifications without departing from the scope of my invention as defined in the appended claims.

I claim:

1. In an apparatus of the class described, the combination of a closed chamber adapted to be submerged in a column of liquid, means for admitting gas under pressure into the chamber, an outlet pipe extending from the chamber, means for admitting liquid from the column of liquid into the said chamber, and automatically fluid actuated means interposed between the said gas inlet, and liquid inlet means to actuate the liquid inlet means to a closed position after a predetermined quantity of liquid has been admitted into said chamber and open said gas inlet means.

2. In a gas lift, the combination of a closed chamber adapted to be submerged in a column of liquid in a well having a gas inlet opening and a liquid inlet opening, valves mounted in said openings, and fluid pressure actuated means interposed between said valves, and operable to actuate the valve to open the liquid inlet and admit a predetermined quantity of liquid into said chamber and operable when the said chamber has received said predetermined quantity of liquid to permit the said valve to close the liquid inlet opening and actuate the gas inlet valve to open the gas inlet and admit gas under pressure into said chamber to lift said liquid from said chamber, and an outlet pipe extending from the chamber.

3. In a gas lift, the combination of a closed chamber adapted to be submerged in a column of liquid in a well having a gas inlet opening, a liquid inlet opening, and a liquid outlet, a gas inlet valve, a liquid inlet valve, and fluid pressure actuated means interposed between said valves and operable to intermittently and alternately actuate said valves to permit a predetermined quantity of liquid to enter said chamber and to be lifted from said chamber through the liquid outlet as a slug.

4. In a gas lift, the combination of a chamber, means for suspending the chamber in submerged position in a column of liquid in a well, the chamber providing a gas inlet opening, a liquid inlet opening and a liquid outlet, a balanced type gas inlet valve, a balanced type liquid inlet valve, and fluid pressure actuated means interposed between said valves and operable to intermittently and alternately open the gas inlet and liquid inlet valves to admit a predetermined quantity of liquid into the gas chamber and to admit

- gas under pressure into the chamber to lift the liquid from the chamber through the liquid outlet of said chamber, and means operably associated with the fluid pressure actuated means and adapted to be adjusted to determine the quantity of liquid to be admitted into the gas chamber from said fluid column.
5. In an apparatus of the class described, the combination of a closed chamber adapted to be submerged in a column of liquid, means for admitting gas under pressure into the chamber, an outlet pipe extending from the chamber, means for admitting liquid from the column of liquid into said chamber, automatic fluid pressure actuated means interposed between the said gas inlet means and liquid inlet means and operable to intermittently and alternately actuate the gas and liquid inlet means to admit a predetermined quantity of liquid from the fluid column into said chamber, close the liquid inlet means and open the gas inlet means to lift the predetermined quantity of liquid from the closed chamber through the outlet pipe as a slug.
6. In an apparatus of the class described, the combination of a closed chamber adapted to be submerged in a column of liquid, means for admitting gas under pressure into the chamber, an outlet pipe extending from the chamber, means for admitting liquid from the column of liquid into said chamber, automatic fluid pressure actuated means interposed between the means for admitting gas under pressure into the chamber, and the means for admitting liquid from the column of liquid into said chamber, to alternately actuate the said means to admit a predetermined quantity of liquid from the column of liquid into said chamber and lift the said liquid from said chamber through said outlet pipe.
7. In an apparatus of the class described, the combination of a closed chamber adapted to be submerged in a column of liquid in a well, concentrically disposed pipes extending from said chamber to the surface of the well, one of said pipes providing a liquid outlet pipe, the other of said pipes providing a gas inlet pipe, means for controlling the admission of gas into said chamber, means for controlling the admission of liquid into said chamber, and automatic fluid pressure actuated means interposed between the gas control means and the liquid control means and operable to actuate said control means alternately to admit a predetermined quantity of liquid into said chamber and to lift the said quantity of liquid from the chamber through the liquid outlet pipe as a slug.
8. In an apparatus of the class described, the combination of a closed chamber adapted to be submerged in the column of liquid, means for admitting gas under pressure into the chamber, an outlet pipe extending from
- the chamber, means for admitting liquid from the column of liquid into said chamber, and automatic fluid pressure actuated means interposed between the gas inlet means and the liquid inlet means and adapted to be actuated by the pressure created by a predetermined head of liquid in said chamber to close the liquid inlet means and open the gas inlet means to lift said predetermined quantity of liquid from said chamber as a slug.
9. In an apparatus of the class described, the combination of a closed chamber adapted to be submerged in a column of liquid, means for admitting gas under pressure into the chamber, an outlet pipe extending from the chamber, means for admitting liquid from the column of liquid into the said chamber, and automatic fluid pressure expansible means interposed between the gas inlet and the liquid inlet means to actuate the liquid inlet means to a closed position after a predetermined quantity of liquid has been admitted into said chamber.
- Signed at Los Angeles, Calif., this 11th day of June, 1928.
